UNITED STATES PATENT OFFICE.

HENRY I. WRIGLEY, OF CHICAGO, ILLINOIS, ASSIGNOR TO UNIVERSAL DRAFT GEAR ATTACHMENT CO., A CORPORATION OF ILLINOIS.

BRAKE MECHANISM FOR RAILWAY CARS.

Application filed January 28, 1924. Serial No. 689,034.

This invention relates to brake mechanism for railway cars and particularly to the anchoring of the chains or cables used therein. The principal objects of the invention are to relieve the strain on the means for fastening the ends of the chains or cables and to permit ready adjustment for taking up slack.

Further objects and advantages of the invention will become apparent as the disclosure proceeds and the description is read in connection with the accompanying drawings in which—

Fig. 1 is a fragmentary plan view showing the invention, applied to a car;

Fig. 2 is a side elevation partly in section;

Figs. 3 and 4 are plan and end elevation respectively of the principal element of the anchoring means;

Fig. 5 is a section taken on the line 5—5 of Fig. 3;

Figs. 6, 7, 8, 9 and 10 are views corresponding to Figs. 1, 2, 3, 4, and 5 respectively, and showing a modified construction.

In Figs. 1 and 2 there is shown a fragment 10 of a car underframe having a bracket 11, sometimes called a brake step, in which a brake staff 12 is journaled. In this instance the brake step includes a bar having one end bent upwardly, as indicated at 13, and riveted to a sill at 14, the other end being supported by an inclined brace 15 connecting it with a cross angle 16.

The power developed by rotating the brake staff 12 is communicated to the brakes through a brake rod 17 having a jaw 18 in which is journaled a power multiplying sheave 19. A chain 20 running over this sheave and fastened thereto at 21 has one end in winding engagement with the brake staff, as indicated at 22, and the other end is anchored to the car frame.

The present invention is particularly concerned with this anchorage. As shown in Figs. 1 to 5, it includes an element, preferably a casting or stamping, having an intermediate portion 23 about which is a chain receiving trough 24. In this instance the intermediate portion 23 is flat to correspond with the bottom of the brake step 11 and is secured thereto by rivets, or bolts 25. The inner wall 26 of the trough is connected with the flat portion 23 and forms a somewhat rounded abutment about which the chain is

laid in a bight, as shown particularly in Fig. 1. As here shown, the trough is substantially U-shaped and the inner wall 26 and outer wall 27 lie substantially parallel on the sides of the intermediate portion. The outer wall is preferably cut away, as indicated at 28, to save material and permit ready access to the chain from what may be called the front.

With the chain looped or formed into a bight about the abutment it becomes a very easy matter to fasten the end, for the bulk of the strain will be taken up by the co-operation between the chain and the abutment. A convenient fastening is had by perforating the walls 26 and 27 and inserting a key 29 through them and a link of the chain 20. Preferably the perforations are in series extended along these walls to permit the chain to be secured in a plurality of different positions. The arrangement shown in Fig. 5 is very convenient where there are six perforations 30 arranged in staggered relation. In order to provide convenient clearance between the heads of the rivets 25 and the bottom of the trough the latter may be inclined, as indicated at 31 in Figs. 4 and 5.

The key 29 may be split, as illustrated best in Figs. 1 and 5, the loop or eye being on the outside and the spread ends being underneath the intermediate portion 23. The bottom of the anchor element is open and therefore affords easy access to the key both in fastening and unfastening.

The advantages of forming a line or chain into a bight about a box, or the like, are so well known that a detailed recital would be superfluous; and it is clear that these advantages will attend the fastening of a chain when it is done in the above described manner. By adding to this a means for ready adjustment the anchorage becomes very desirable.

In Figs. 6 to 10 inclusive, the alternative construction is shown to illustrate how modifications may be made to suit particular conditions. This form is especially adapted for cars where no brake step is used and there is no other bracket or the like in convenient position. In this case the outer wall may be equipped with flanges 34 adapted to be fastened by rivets 35, or the like, to any suitable part of the car, as for example, the angles 36.

Instead of inclining the trough and perforating its walls, one side of the trough may be provided with a top 37 and the perforations 38 made through this top and the bottom of the trough. The key may then be inserted in any pair of the selected holes and fastened as conveniently as before. This construction makes one side of the trough substantially box-shaped as indicated at 39 in Fig. 9. The other side of the trough may also be box-shaped, or may simply have a tie or brace 40 connecting the top edges of the trough.

The inner wall 41 of the trough may be connected to an intermediate portion 42, as in the other form, and is preferably bent, as shown at 43, to form an abutment about which the chain 44 is looped into a bight.

Here again, the walls of the trough are substantially parallel and the trough is curved like a U with the legs extending substantially straight and parallel. Preferably the box-like portion 39 is somewhat wider than the corresponding portion of the other leg to give clearance for the chain as it is moved from one to another of the staggered holes 38.

I claim as my invention:—

1. In a brake mechanism, for railway cars, the combination of a brake shaft, a brake rod, a sheave mounted in the brake rod, a chain looped about the sheave with one end in winding engagement with the shaft and means for anchoring the other end of the chain including a curved chain receiving trough, one end of which is aligned with the brake rod and the other end of which is substantially parallel with the first, and means for making the end of the chain fast to the latter end of the trough.

2. In a brake mechanism for railway cars, the combination of a brake shaft, a brake rod, a sheave mounted in the brake rod, a chain looped about the sheave with one end in winding engagement with the shaft and means for anchoring the other end of the chain including an element having an intermediate portion and a curved chain trough extending about the intermediate portion and opening laterally from the plane of said portion for supporting the chain, means for securing the chain adjacent one end of the trough and means for securing the trough to a car.

3. In a brake mechanism for railway cars, the combination of a brake shaft, a brake rod, a sheave mounted in the brake rod, a chain looped about the sheave with one end

in winding engagement with the shaft and means for anchoring the other end of the chain including a chain receiving trough opening upwardly and curved in a substantially horizontal plane, and means for securing the end of the chain adjacent one end of the trough.

4. In a brake mechanism for railway cars, the combination of a brake shaft, a brake rod, a sheave mounted in the brake rod, a chain looped about the sheave with one end in winding engagement with the shaft and means for anchoring the other end of the chain including an outer wall and an inner wall, the latter having a rounded abutment about which the chain is formed into a bight, and means for securing the chain between said walls.

5. In a brake mechanism for railway cars, the combination of a brake shaft, a brake rod, a sheave mounted in the brake rod, a chain looped about the sheave with one end in winding engagement with the shaft and means for anchoring the other end of the chain including an abutment about which the chain is formed into a bight, and means including a trough opening laterally from the plane of said abutment for supporting said chain, and means for making the end fast between the abutment and the sheave.

6. In a brake mechanism for railway cars, the combination of a bracket having a substantially flat intermediate portion, a chain receiving trough extending along both sides and one end of the intermediate portion of the bracket and having its bottom spaced laterally from said intermediate portion, a chain in the trough, and means for making a link of the chain fast to one end of the trough.

7. In a brake mechanism for railway cars, the combination of a brake step, a bracket having a substantially flat portion secured to the step, a chain trough lying below the flat portion and having its inner wall connected with the sides and one end of the flat portion, a chain in the trough and means for attaching the chain to one end of the trough.

8. An anchoring device for a railway brake chain comprising a member having an abutment about which a brake chain is adapted to form a bight, means for supporting the portion of said chain about said abutment in all positions of use, said means including a trough opening in a direction at substantially right angles to the plane of said abutment.

HENRY I. WRIGLEY.
